COIN DETECTING DEVICE FOR SLOT
MACHINES

Theodore Bibicos, Cleveland, Ohio

Application February 4, 1937, Serial No. 123,976

2 Claims. (Cl. 194—103)

This invention pertains to coin-detecting devices, and has particular reference to slot machines to prevent the use of slugs or other substitutes for coins to operate the machine. This invention is in some respects an improvement on the machine shown in my Patent No. 2,085,626.

The device is particularly adapted for use on machines in telephone pay stations.

The object of the invention is to provide an improved coin-measuring and weighing device which automatically separates, deflects and ejects slugs, spurious coins and the like.

In the accompanying drawings:

Fig. 1 is a front elevation of the device partly in section and with the cover removed.

Fig. 2 is a section partly in elevation on line 2—2 of Fig. 1.

Fig. 3 is a section partly in elevation on line 3—3 of Fig. 1.

Fig. 4 is a fragmentary section on line 4—4 of Fig. 1.

Fig. 5 is an elevation of a fragmentary portion of the device as indicated by line 5—5 of Fig. 1.

Fig. 6 is a similar elevation on line 6—6 of Fig. 1.

Fig. 7 is a perspective view of Fig. 1 except that the upper gates are shown in the open position.

Figs. 8 and 9 are diagrammatic perspectives illustrating the closed and open positions of the upper gates, respectively.

Figs. 10 and 11 are perspectives of the lower gates, in different positions respectively.

Referring again to the illustrations; a base plate or wall 10 has mounted thereon an upper coin guide 11, with a coin receiving slot 12 at its top edge and a substantially rectangular opening or orifice 13 near the top thereof and angularly disposed in the side wall thereof.

A boss 10a on the wall 10 is so disposed on the wall 10 as to form a buffer for small slugs as they pass the orifice 13.

The coin guide 11 is slotted to form a passageway 14 as indicated by the dotted lines in Fig. 1; and a curved projection 15 extends downwardly beside the aperture 16 in the lower edge of said coin guide.

A spring 17 is secured to the inner wall of the passageway 14 adjacent to the aperture 16 in the coin guide 11, said coin guide being secured to the wall 10 by bolts 18.

A small pivoting gate 19 is mounted on the wall 10 and disposed to the left and near the top of the part 15 while a larger pivoting gate 20 is mounted to the right of and slightly below the projection 15 on pivot pins 21 and 22 respectively.

A pair of stops 23 and 24 are mounted on the

wall 10 in such position as to limit the opening of gates 19 and 20 respectively.

An adjustable weight 25 is pivotally secured to the gate 20 at its outer end, by a pivot 26; a flanged portion 20a of the gate 20 limits the pivotal movement or swing of the weight 25, said weight always moving to a perpendicular position regardless of the position of the gate 20.

A lower coin guide 27 is mounted on the wall 10 below the gates 19 and 20, a slotted aperture 10 28 in the coin guide 27 being disposed below the gates 19 and 20 in such position as to receive the coins as they fall through the open gates.

The passageway 29 in the guide 27 is indicated by the dotted lines shown in Fig. 1 and terminates in an aperture 30 beneath a curved projection 31, said guide being secured to the wall 10 by bolts 18a.

A spring 27a is secured to the inner wall of the passageway 29 to the left and adjacent the aperture 30.

A second pair of pivoting gates 32 and 33 are mounted on the wall 10 below and adjacent to the projection 31, the smaller gate 32 being mounted on a pivot pin 34 to the right of the projection while the larger gate 33 is mounted on a pivot pin 35 to the left and below the said projection.

A pair of stops 36 and 37 are disposed below the said gates respectively in such manner as to limit the pivoting of said gates.

A balancing weight 38 is pivotally secured to the outer end of the larger gate 33 below the flange 33a of said gate.

A pair of receptacles 39 and 40 respectively are placed below the gates, that on the left being so placed that genuine coins will drop therein, while that on the right is so disposed that all slugs or spurious coins are automatically received therein. A cover 41 is secured over the mechanism by bolts 42 and 42a through the said cover and in the bosses 43 and the apertures 44 respectively.

In operation, a small slug "A" entering the slot 12 moves down the passageway 14 in the upper coin guide 11 until it strikes the buffer 10a which causes the slug "A" to fall outward through the orifice 14 and downward into the slug receptacle 40.

A large slug "B" or a heavy slug "C" being 50 larger in circumference than small slug "A", passes the orifice 13 and in moving downward strikes the spring 17, retarding its downward speed; slug "B" or "C" in passing through the aperture 16 beneath the projection 15 strikes the 55

gates 19 and 20, slug "B" being lighter in weight does not tip the gates enough to cause them to open fully, but the impact of the slug does cause the gates to open slightly, the weighted ends then 5 return the gates to their original position which thus pushes the slug up and outward causing said slug to roll outward along the top surface of gate 20 and drop downward into slug receptacle 40; slug "C" being heavy, drops upon 10 the gates 19 and 20 causing them to open, the slug "C" dropping through the open gates and into the coin guide 27 through the slotted aperture 28 in the top edge thereof, striking the spring 27a which thus retards the velocity of 15 the slug; the slug "C" then drops through the aperture 30 beneath the projection 31 and on to the gates 32 and 33 causing them to open and drop the slug "C" into the slug receptacle 40.

A coin "D" follows the procedure of slug "C" 20 except that it does not open the lower gates 32 and 33, but rolls outward along the top of gate 33 and drops within the coin receptacle 39.

Figs. 8 and 9 illustrate the operation of the upper gates 19 and 20 while Figs. 10 and 11 illustrate the operation of the lower gates 32 25 and 33.

Obviously the weight 25 is such that the gate 20 will not open under the weight of the light slug "B" and will eject the same, but will open 30 and pass a heavy slug "C" or the proper coin

"D". Then the weight 38 is such that the gate 33 will open and eject a heavy slug "C", but will not be opened by a coin "D" and will therefore pass the same to the cash box 39. In short, small slugs "A" will be tilted out at the opening 5 13, light slugs will be thrown out at the upper gates; and heavy slugs at the lower gate. When the gates are closed they combine to form an inclined trackway leading from the outlet of the chute. 10

I claim:

1. The combination with a coin chute, of a pair of gates below the outlet therefrom, said gates swinging toward and from each other and the outlet, and being weighted to normally close 15 with the ends of the gates in contact with each other, the pivot of one gate being located higher than that of the other gate, and the gates forming an inclined trackway from the outlet when they are in contact. 20

2. The combination with a coin chute, of upper and lower gates below the outlet therefrom, said gates swinging toward and from each other and being weighted to normally close with the end of the lower gate in contact with the end 25 of the upper gate, whereby the latter forms a stop for the former, and producing an inclined trackway from the outlet when said ends are in contact.

THEODORE BIBICOS. 30
